UNITED STATES PATENT OFFICE.

BERNARD MORGAN, OF NEWPORT, RHODE ISLAND.

IGNITING DEVICE FOR GAS-BURNERS.

1,123,849.

Specification of Letters Patent.

Patented Jan. 5, 1915.

Application filed March 7, 1914. Serial No. 823,065.

To all whom it may concern:

Be it known that I, BERNARD MORGAN, a subject of the King of Great Britain, and a resident of Newport, in the county of Newport and State of Rhode Island, have invented certain new and useful Improvements in Igniting Devices for Gas-Burners, of which the following is a specification.

My invention relates to igniting devices 10 designed for use with gaseous fuel burners, and particularly to igniting devices of the type in which a spark or stream of sparks is produced by the action of an abrasive member moving in contact with a spark producing element or member made of a pyrophoric substance such, for example, as of an alloy containing a metal or metals of the cerium group and a sub-oxid of said metal or metals, or an alloy of cerium and iron, and in which 15 igniting device the spark or sparks are projected into the stream of gas or combustible mixture to be ignited; such igniting devices being commonly known and referred to by those skilled in the art to which my invention relates as frictional or pyrophoric igniters.

The objects of my invention are to provide a manually operable igniting device of the type above referred to which may be 20 readily attached to an ordinary form of gaseous fuel burner, such, for example, as a lighting burner, and used to ignite the gas or combustible mixture issuing therefrom; to provide an igniting device which may be 25 readily and cheaply produced by approved manufacturing processes, and one which will be simple in construction, so that it will be unlikely to get out of order in use or fail to operate, yet which will be effective for the 30 purpose for which it is provided; and to provide such other and further improvements in and relating to igniting devices as are hereinafter described and claimed and illustrated in the drawing accompanying 35 40 45 50

of lighting burner; Fig. 2 is a view showing a section of my device upon a plane indicated by the line 2—2, Fig. 3, looking toward the left; Fig. 3 is a view showing my device apart from the burner and as seen from a position to the left of Fig. 2; Fig. 4 is a view showing a section taken upon a transverse plane indicated by the line 4—4, Fig. 3; Fig. 5 is a view showing the frame 60 of my device flattened out, so as to illustrate how the same is produced from a suitable blank. Fig. 6 is a view upon a larger scale and principally in section, upon a transverse plane indicated by the line 6—6, 70 Fig. 2; and, Fig. 7 is a view drawn to the same scale as Fig. 6 and showing certain elements of my device.

Referring to the drawing, the reference numeral 7 designates a suitable frame 75 designed to be secured to a gaseous fuel burner 8, as shown in Fig. 1, the burner shown in that figure being a common form of burner designed to burn acetylene gas and to be used in an automobile headlight or similar 80 lamp. This frame serves as a support for the various parts hereinafter specifically referred to and which parts, together with the frame, form my improved igniting device. The frame is made from a blank cut 85 from a thin sheet metal plate by performing suitable bending, shaping, and similar operations thereupon as by means of suitable dies, to thereby cause the blank to assume the form of the finished frame, the form of 90 the blank being obviously such that the frame may be produced therefrom in the manner herein referred to. The frame is shown flattened out in Fig. 5 and, although the blank may depart somewhat from the 95 outline appearing in this figure, said blank will be of approximately the form illustrated in said figure.

The frame 7 is provided with two oppositely located arms 9 having holes 10 adjacent their free ends through which a bolt or screw 11 extends and by means of which the ends of the arms may be drawn together and the device as a whole clamped in place upon the burner 8, as shown in Fig. 1 and as will 100 be understood. Said frame is also provided with two oppositely located ears 12 which serve to support the abrasive member of my device, and with two lugs 13 adapted to fit over opposite edges of a plate or 105 cover 14 to thereby retain the same in place; the arms, ears, and lugs being formed by 110

In the drawing: Figure 1 is a view illustrating my improved igniting device in perspective and attached to a common form

bending corresponding portions of the blank from which the frame is made to cause said elements to assume their proper positions in the finished frame, as hereinbefore explained.

8 The reference numeral 15 designates a recess or pocket extending longitudinally of the frame and formed in the blank from which the same is made as by means of suitable dies, as above explained, the open side of said recess being closed by the plate or cover 14 which extends across the recess and which cover in turn is held in place by the overlying lugs 13, whereby a chamber is 15 formed within which a spark producing member or element 16 is located, the same being resiliently supported upon and pressed outward by a spring 17 the lower end of which abuts against the end wall 18 at the 20 lower end of the recess 15, as best shown in Fig. 2.

The ears 12 serve as supports for the ends of a transverse pin 19 at the middle portion of which a swinging arm 20 is loosely supported and which arm is held in its lowermost position illustrated (or suddenly returned to that position after having been swung upward about the pin as a center) by means of a suitable spring member 30 shown as comprising two coil springs 21, surrounding the pin 19 and located one upon either side of the arm 20; and which springs are connected with one another through a central loop 22 which bears upon 35 the upper side of the arm 20, as best shown in Fig. 2, the springs and loop being formed from a single piece of wire the free ends 23 of which bear against a cross-bar 24 of the frame.

40 The arm 20 serves as a support and carrier for an abrasive member 25, the same being curved and preferably in the form of a segment of a ring the extent of which is such that when the abrasive member is in 45 position it is held in place by the engagement of the free ends 26 thereof with the enlarged head 27 of the arm 20, the periphery of which head is curved to correspond with the inner surface of the abrasive member as 50 shown in Figs. 2 and 7, and could leave the head only by a lateral or sidewise movement because of the fact that the free ends of the abrasive member are a less distance apart than the diameter of the head. Such a 55 movement, however, cannot occur in practice because of the fact that there is no force tending to move the abrasive member sidewise, and because of the fact that such movement would be arrested by the side 60 edges of an opening 28 provided in the frame, see Fig. 5, and into which the abrasive member extends, and because of the further fact that the inner coils of the springs 21 naturally overlie and are located 65 close to the sides of the seat 27 and abrasive

member as best shown in Fig. 3. The periphery of the abrasive member is serrated as shown, and moves in contact with the spark producing element 16 as the arm 20 is moved upward manually and returned by 70 the action of the springs 21; whereby particles of the pyrophoric substance of which the spark producing member is made are torn therefrom and projected into the air, whereupon the particles take fire and produce sparks in accordance with the well known phenomena associated with such substances.

75 In view of the premises it will be appreciated that I have produced an igniting device in which the movement of the abrasive member which results in the production of a spark or series of sparks, (the movement in the direction indicated by the arrow Fig. 2) is accomplished suddenly and with great 80 rapidity because of the direct action of the springs 21 upon the arm 20, which springs act to return the arm to its initial position after it has been swung upward by the hand, and then released.

85 The abrupt and rapid action of the abrasive member upon the spark producing elements results in a hotter and larger (or fatter as expressed by persons having to do with problems involving the ignition of a 90 gas) spark than would be the case if the movement of the abrasive member took place less rapidly, as because of the retarding influence of mechanism intermediate the abrasive member and the spring or springs 95 100 whereby the same is operated, or devices connected with the operating member for operating the same; the larger and hotter spark being due, according to my understanding, to the fact that a greater number 105 of particles of the pyrophoric substance which forms the spark producing member are torn therefrom, and which particles remain closer together as they are thrown into the air, than would be the case if the movement of the abrasive member took place less rapidly. The resulting spark or sparks are also thrown farther, and better into the stream of combustible mixture to be ignited, than would be the case if the movement of 110 the abrasive member occurred less abruptly. Again, in my improved igniting device the abrasive member is of such a form that it cannot become accidentally disengaged from the member or arm by which it is supported, 115 and, finally, the frame of my device is of such a form and is so designed with reference to the end in view that it may be produced at a minimum of cost, and by approved and simple processes of manufacture.

120 Having thus described and explained my invention, I claim and desire to secure by Letters Patent:—

1. An integral frame for an igniting de- 125

vice of the class described, the same being formed from a sheet metal blank and having two oppositely located arms adapted to engage a burner, two oppositely located ears 5 between which an abrasive member may be supported, and a recess located between said arms and ears and adapted to contain a spark producing element.

2. An integral frame for an igniting device of the class described, the same being formed from a sheet metal blank and having two oppositely located arms adapted to engage a burner, two oppositely located ears between which an abrasive member may be 10 supported, a recess located between said arms and ears and adapted to contain a spark producing element, and lugs located adjacent said recess and adapted to engage a cover for said recess.

3. An igniting device of the class described comprising a frame adapted to be secured to a burner; a spring pressed spark producing element supported by said frame; two oppositely located ears carried by said 25 frame; a swinging arm supported between said ears; an abrasive member separate from and supported upon said arm and partaking of the swinging movements thereof, and which abrasive member is adapted to move 30 in contact with said spark producing element; and a spring acting upon said arm to return the same to its initial position after it has been moved therefrom.

4. An igniting device of the class described comprising an integral frame formed from a sheet metal blank and having two oppositely located arms whereby the device may be secured to a burner, two oppositely located ears for supporting a pivotally supported abrasive member, and a recess located between said arms and ears and adapted to contain a spark producing element; a spring pressed spark producing element located within said recess; an oscillating 45 abrasive member supported by said ears and adapted to move in contact with said spark producing element; and a spring operatively connected with said abrasive member and adapted to return the same to its initial position after it has been moved therefrom.

5. An igniting device of the class described comprising a frame adapted to be secured to a burner and which frame is provided with a recess; a cover secured to 55 said frame and extending longitudinally of and across said recess; a resiliently supported spark producing element located within said recess; two oppositely located ears carried by said frame; a swinging arm supported 60 between said ears; an abrasive member carried by said arm and adapted to move in contact with said spark producing element; and a spring acting upon said arm to return the same to its initial position after it has been moved therefrom.

6. An igniting device of the class described comprising a frame adapted to be secured to a burner and which frame is provided with a recess; a cover extending across said recess; lugs upon said frame and adapted to engage said cover to hold it in place; a resiliently supported spark producing element located within said recess; a pivotally supported oscillating abrasive member supported from said frame and adapted to move in contact with said spark producing element; and a spring acting upon said abrasive member to return the same to its initial position after it has been moved therefrom.

7. An igniting device of the class described comprising a frame adapted to be secured to a burner and which frame is provided with a recess; a cover secured to said frame and extending longitudinally of and across said recess; a spring pressed spark producing element located within said recess; two oppositely located ears carried by said frame; a transverse pin extending between said ears; a swinging arm supported upon said pin; an abrasive member carried by said arm and adapted to move in contact with said spark producing element; and two coil springs each surrounding said pin and located one upon each side of said arm, and which springs are operatively connected with said arm to return the same to its initial position after it has been moved therefrom.

8. In an igniting device of the class described; a suitable frame adapted to be supported from a burner; a spark producing element carried by said frame; a pivotally supported swinging arm supported from said frame and having an enlarged head; a curved abrasive member the free ends of which engage said enlarged head to thereby hold said abrasive member in place, and which abrasive member moves in contact with said spark producing member; and a spring acting upon said arm to return the same to its initial position after it has been moved therefrom.

9. In an igniting device of the class described; a suitable frame adapted to be supported from a burner; a spark producing element carried by said frame, a pivotally supported swinging arm supported from said frame and having an enlarged head; an abrasive member in the form of a segment of a ring the free ends of which are a less distance apart than the diameter of said head, whereby said ends embrace the head to thereby hold the abrasive member in place, and which abrasive member moves in contact with said spark producing member; and means for swinging said arm about its pivotal support.

10. An igniting device of the class described comprising an integral frame

43
formed from a sheet metal blank and having two arms whereby it may be secured to a burner, two oppositely-located ears, and a recess intermediate said arms and ears and adapted to contain a spark producing element; a resiliently supported spark producing element located within said recess; means for retaining said element in place in said recess; an oscillating abrasive member supported between said ears and adapted to move in contact with said spark pro-

ducing element; and a spring adapted to return said abrasive member to its initial position after it has been moved therefrom.

In testimony whereof I have signed my ¹⁵ name to this specification in the presence of two subscribing witnesses.

BERNARD MORGAN.
